No. 12,872

Apr. 11, 1882

UNITED STATES PATENT OFFICE.

IDA F. CLARK, OF ALBANY, ASSIGNOR TO WARREN, FULLER & CO., OF NEW YORK, N. Y.

DESIGN FOR WALL-PAPER.

SPECIFICATION forming part of Design No. 12,872, dated April 11, 1882.

Application filed February 13, 1882. Term of patent 3½ years.

To all whom it may concern:

Be it known that I, IDA F. CLARK, a citizen of the United States, residing at the city, county, and State of New York, have invented and 5 produced a new and original Design for Wall Papers, of which the following specification is a clear description, reference being had to the accompanying drawing, forming part thereof.

The said drawing represents an elevation of 10 a section of my design for wall-paper.

The section of ornament under treatment is divided by transverse or horizontal bands A, A', A², D, D', and D² into four several fields of ornament, which are respectively lettered or 15 marked on the drawing B, C, E, and F. The transverse bands A, A', and A² are located respectively at the bottom of the section under treatment at about four to six inches (more or less) above the bottom of the said section and 20 at about one-third of the height of the section above the bottom, thus dividing off the ornamental fields B and C. The said bands A, A', and A² are each composed of twisted or imitation rope-work, and each of them may be one 25 or two inches wide, more or less. The transverse bands D, D', and D² are each several inches in width, and ornamented with figures resembling fish-scales. The band D is placed below the center of the section under treatment and next above and contiguous to the rope band A². The bands D' and D² are placed 30 respectively at the bottom and top of the cornice-panel F. At the top of the band D, and at both the top and bottom of the bands D'

and D², there are placed, and in close continuity with the said bands, broad stripes d, of any desired coloring. The central and largest panel or field of ornament, E, is placed between or bounded respectively at its bottom and top sides by the transverse bands D d and D d. 40 The base panel C is enriched or ornamented with illustrations of subaquatic plants and ichthyological specimens, while the sub-base B is filled with a lower order of subaquatic plants and marine shells. The intermediate or principal panel, E, is filled with a lace-like work formed by geometrical lines, behind which formation is a shadowy outline of cloud-work. The cornice-panel F is richly filled with subaquatic plants and marine shells. 45 50

The lines and figures forming the above-described ornamental design may be printed or painted in any desired colors and on any desired coloring of background.

Having described my invention or design, I 55 claim—

The ornamental design for wall-paper or paper-hangings, consisting of the transverse lines or bands A, A', A² and D, D', and D² of geometrical figures, with their intermediate fields 60 of ornament, B, C, E, and F, the said fields of ornament being enriched with ichthyological representations, subaquatic vegetation, and geometrical figures, substantially as described.

IDA F. CLARK.
